CONTAINER

Harold J. Wallace, Utica, N. Y., assignor to Fonda Container Company, Inc., Utica, N. Y., a corporation of New York

Application December 16, 1937, Serial No. 180,181

4 Claims. (Cl. 229—4.5)

This invention relates to containers having a body formed of laminations of fibrous material, such as paper, and adapted for the handling and distribution of both solid and liquid materials. 5 More particularly, the invention is concerned with a novel container of the type described, in which the body is generally of frusto-conical shape so that a plurality of the empty containers may be nested together to make a compact package for shipping and storage.

Nesting containers as commonly made heretofore have included a body made either of a single blank of material wound convolutely, or of one or more blanks wound helically with the edges of 15 adjacent convolutions overlapping. Such overlapped edges, present in each form, produce shoulders, both on the inner and outer surfaces of the body, and as a result, difficulty is encountered in providing such containers with tight 20 fitting covers. The covers ordinarily used with containers of this sort either are formed to enclose the end of the container and make tight contact with the outer wall or are discs which are snapped into a recess in the inner wall. In 25 either case, the presence of the shoulders referred to prevents the cover from fitting snugly and leakage may occur along the face of each shoulder. In addition, the convolutely wound container has a line of weakness represented by 30 the seam which extends in a straight line from top to bottom of the body.

The present invention is directed to the provision of a nesting container which overcomes the defects of the prior containers above referred 35 to and the new container is so constructed that the body has no localized line of weakness and no shoulders or other projections on either wall which interfere with the use of a tight fitting cover. The container body is of frusto-conical 40 shape throughout at least the greater part of its length, and of substantially uniform thickness throughout its circumference. The body is made up of a plurality of laminations of paper or other suitable fibrous sheet material and each lamination is a separate blank of material wound substantially helically with its adjacent edges abutting to define a seam of the same thickness as the remainder of the laminations. The several 45 laminations are secured together face to face with their respective seams offset and the weakness resulting from the seams is thus distributed circumferentially about the body.

One end of the container body is fitted with a closure permanently secured in place and the 50 other end is closed by a removable cover. A cover

advantageous for the purpose comprises a cylindrical side portion and a circular top secured permanently in place therein. When such a cover is to be used, the container is formed with a cylindrical end section of an outer diameter substantially equal to the inner diameter of the side portion of the cover, so that the cover will make a frictional fit with the end section throughout the circumference of the latter.

It is advantageous to provide the top of a cover 10 of this type with an annular groove adapted to receive the upper edge of the container body. The annular groove in effect forms a valve seat that protects the upper edge of the container body from injury that might be caused by substances in the container coming in contact with it and seeping into the inner porous structure of the paper. The use of such a valve seat also increases the effectiveness with which the body is closed by the cover.

Although covers substantially as described are particularly well suited for use with the new container, covers of other forms also may be employed, as, for example, the simple disc type commonly used on milk bottles.

The invention may be better understood from the following description considered in connection with the accompanying drawing, in which

Fig. 1 is a side view of a container formed in accordance with the invention, the cover of the 30 container being removed and shown above the body;

Fig. 2 is a vertical cross-section through the new container, showing one form of cover in place;

Fig. 3 is a vertical cross-section through a container of modified form having a different type of cover;

Fig. 4 is a vertical cross-section through the lower portion of a container having an alternative 40 bottom closure;

Figs. 5 and 6 are plan views of the blanks from which outer and inner layers, respectively, of the body of the new container are made; and

Fig. 7 is a plan view of a composite blank such 45 as may be employed in the manufacture of the new container.

The containers shown include a body 10 which is of frusto-conical shape throughout at least the greater portion of its length, so as to permit nesting together of a plurality of the containers. This is made of a plurality of laminations of suitable fibrous sheet material (e. g. paper), and in the various forms illustrated in the drawing, an outer lamination 11 and an inner lamination 50 55

12 are employed. Each lamination is formed of a blank wound substantially helically with its opposite ends abutting to define a seam 13, and as the seams extend substantially helically the 5 length of the container, the weakness of the seams is distributed circumferentially about the container. The laminations are secured together by any suitable adhesive and their respective 10 seams are offset but run helically in substantially the same direction so that crossing of seams is avoided.

The blanks from which the laminations 11 and 12 are made are, respectively, shown in plan in Figs. 5 and 6. The blanks 14, 15 are generally of 15 the form of a parallelogram with two angles obtuse and two acute. The blank 14 has two opposite sides 16 and 17 cut on substantially arcuate lines curving in the same general direction but not having coincident centers and these arcuate 20 edges 16 and 17 form, respectively, the lower and upper edges of the body to be made. The other two opposite edges 18 and 19 of blank 14 are cut on substantially straight lines which, if extended, would intersect one another at an acute angle 25 of, for example, about 30°, this angle varying with the degree of taper desired in the body. The sides 18 and 19 abut when the blank 14 is wound, and the length of these sides, measured along the lines on which they are cut, should be equal. 30 As a result, the altitude of the blank adjacent the side 18 is slightly less than the corresponding dimension adjacent the side 19. The blank 15 for the inner lamination member is cut substantially the same as the blank 14, and it has two 35 opposite sides 20, 21 cut on substantially arcuate lines and other sides 22, 23 cut on straight lines which, if extended, would intersect at a small angle. The blank 15 is cut to slightly smaller dimension than the blank 14 so that the blanks 40 when wound will fit together tightly.

Various methods may be employed for winding the blanks to form the body, and in Fig. 7 there is illustrated a development of the blanks in the relation which they bear to one another in 45 the completed body. As shown, the two blanks lie with their upper and lower arcuate edges substantially in alignment and are offset lengthwise by about half their length.

Any suitable bottom closure may be employed 50 at the lower end of the body and in the containers shown in Figs. 2 and 3, the bottom closure is a disc-shaped member 24 of paper or other suitable material, having its edge turned downwardly to form a flange 25, the edge of this flange being turned upwardly to form an inner annular 55 bead 26. The disc is inserted in the body and the lower edge of the latter is turned inwardly and upwardly to form the inner wall 27 of an annular 60 channel 28 in which flange 25 and bead 26 of the closure are received. In the operation of securing the bottom in position, the inner wall 27 may be creased inwardly to form a bead 29 which overlies bead 26 on the disc 24 and this results in 65 the closure being held more securely in place. The free edge 30 of the inner wall 27 of the channel then lies within an annular recess 31 formed in the closure adjacent the flange 25, where it is held by the inner wall 32 of the 70 recess 31.

The modified form 33 of bottom closure, shown in Fig. 4, consists of a disc of paper or other suitable material having a downwardly turned flange 34 along its edge. The closure 33 is mounted in 75 the lower end of the container body 10 with the

flange 34 adhesively secured to the inner lower wall 35 of the body.

The shape of the upper end of the container depends on the type of cover to be employed. In the container shown in Fig. 2, the cover comprises 5 a cylindrical portion 36 and a top 37. To secure the top in position, one edge 38 of the cylindrical portion is turned inwardly to define a channel 39 and the edge of the top is turned to form an annular flange 40 which enters this channel. The outer edge of flange 40 is turned over to form a bead 41, and the inner wall 38 of the channel 39 may be crimped inwardly to form a bead 42 engaging with the bead 41. The free edge 43 of the inner wall 38 enters a circumferential recess 44 formed in top 37 near the side portion 36 and is held in place by the inner wall 45 of this recess. 10 15

In order that covers of the type described may be mounted on body 10 with a tight fit, the body is formed with a short cylindrical end section 46. 20 This section has an outer diameter substantially equal to the inner diameter of the side portion 36 of the cover, so that the side portion makes a close fit with the end section of the body.

For some uses, it may be desirable to provide 25 the container with a cover which prevents the contents from reaching the end edge of the body. For this purpose, an annular groove 47 adapted to receive the edge of the body is formed in the top 37 of the cover. This groove functions in 30 the manner of a valve seat to receive the upper edge and protect it from injury that might be occasioned by contact thereof with contents, particularly liquid contents, of the container. A cover with groove 47 is particularly effective in 35 conjunction with the new containers, because the container wall is of substantially uniform thickness throughout its circumference, and there are no shoulders or other irregularities of substantially greater or less thickness than the average that 40 form crevices through which liquid materials can pass.

A modified form of cover that may be used with the new container described is shown in Fig. 3. In this modification, the cover 48 is a disc of 45 paper or other suitable material, and the container body, which may have a cylindrical end section or not, as desired, is provided with a circumferential groove 49 in its inner wall near the upper edge. The internal diameter of the container body measured across the groove 49 is 50 substantially equal to the diameter of the cover 48, so that the latter may be pressed into the upper end of the body until the edge of the cover enters the groove 49, whereupon the cover is held 55 firmly in position.

I claim:

1. A container comprising a body of frustoconical shape throughout at least the greater part of its length and of uniform thickness 60 throughout its circumference, said body comprising laminations of fibrous sheet material, each lamination being formed of a blank wound substantially helically with its edges abutting and defining a seam, the weakness resulting from 65 said seam being distributed circumferentially about the body, and said laminations being secured together face to face with their respective seams offset, and a closure secured to said body to close one end thereof.

2. A container comprising a body of frustoconical form throughout the greater part of its length and of uniform thickness throughout its circumference, said body being made up of laminations of fibrous sheet material, each lami- 70 75

5 nation being formed from a blank wound substantially helically with its edges abutting, the abutting edges of one lamination being offset from those of the next lamination, said laminations being secured together face to face to form the body and said body having one end thereof shaped to form a cylindrical section, and a closure secured to the body to close the end remote from the cylindrical section.

10 3. In a container, a body of frusto-conical form throughout at least the greater part of its length, said body having smooth inner and outer surfaces and comprising laminations of fibrous sheet material, each lamination being formed of a blank wound substantially helically with its edges abutting and defining a seam, the weakness resulting from said seam being distributed circum-

ferentially about the body, said laminations being secured together face to face with their respective seams offset, the body being formed with a circumferential channel in its inner wall near its larger end.

15 4. A blank for a body member of a container comprising a sheet of fibrous material cut generally in the shape of a parallelogram with two opposite angles obtuse and the other two opposite angles acute, two opposite sides of said blank being cut on substantially arcuate lines curving in substantially the same direction, and the other two opposite sides being cut on substantially straight lines which, if extended, would intersect at a relatively small angle.
